UNITED STATES PATENT OFFICE.

AUGUST ERICKSON, OF MINNEAPOLIS, MINNESOTA.

FURNACE OR STOVE STRUCTURE.

Application filed April 2, 1928. Serial No. 266,589.

This invention relates to a stove or furnace of the hot air, hot water or steam type, which furnaces are now commonly used in heating dwellings or other buildings.

5 It is an object of this invention to provide a simple structure of furnace in which the fuel is very efficiently used, and which comprises a drum of annular shape surrounding a chamber into which the products of 10 combustion pass, and about which said products pass, whereby said drum is very efficiently heated, said drum containing the heated medium.

15 It is another object of the invention to provide a furnace having a fire pot with a cylindrical chamber thereabove, having an annular chamber disposed about said cylindrical chamber, adapted to carry the heated medium of the furnace surrounding said first mentioned chamber and extending thereover, said annular chamber having a central opening through the top thereof, an outer chamber being provided about said annular chamber for the passage of the products of combustion.

25 These and other objects and advantages of the invention will be fully set forth in the following description made in connection with the accompanying drawings, in which like reference characters refer to similar parts 30 throughout the several views and in which:—

Fig. 1 is a central vertical section through a furnace embodying the invention, the same being of the hot air type;

Fig. 2 is a top plan view of the device shown in Fig. 1;

Fig. 3 is a central vertical section of a furnace embodying the invention and which is of the hot water or steam type; and

Fig. 4 is a top plan view of the device shown in Fig. 3.

Referring to the drawings, particularly Figs. 1 and 2, a furnace is shown having the base plate having a vertical wall or partition 5^a extending upwardly adjacent one side 45 thereof, with which connects a horizontal partition 5^b. The partitions 5^a and 5^b have a flange 5^c which supports a grate member 6 which may be of any desired construction, the same in the embodiment of the invention illustrated, being shown as formed of a plate having slots extending thereacross. A fire 50 pot 7 is supported on partitions 5^a and 5^b and has a forwardly extending chamber 7^a forming the charging passage therefor, which passage has the charging door 8 at its front

end. The space between the base 5 and partition 5^b forms the ash pit which is provided with an ash door 9 having a plurality of openings 9^a therein, arranged in the arc of a circle, said door 9 also having a draft door 60 or plate 10 thereon carried on a screw shaft 11 having a handle 11^a at its front end, which screw is threaded into a central boss on the door 9. A shell 12 is supported on the top of the fire pot 7, being received in a channel 65 formed by flanges 7^b on the top of said fire pot, which member 12 has an annular chamber 12^a therein having an inwardly extending top portion surrounding a cylindrical upper portion 12^c open at its top and bottom. The 70 member 12 at its inner and lower side has an inwardly extending flange 12^d to which is bolted the bottom and outwardly extending flange 13^a of the member 13, which member is in the form of an inverted pot or shell, 75 the same thus being closed at its top and being illustrated as tapering upwardly slightly toward its closed end. An outer shell 14 of general cylindrical shape extends upwardly from the base member 5 and at the front portion of the furnace from the top of the fire pot 7, said shell being spaced from the member 12 to form a chamber thereabout. The top plate 15 fits over the top of the shell 14 and has a depending flange extending around 80 the top of said shell. The top plate 15 has an upwardly extending flange 15^a at one side surrounding an opening leading therefrom, to which is connected the pipe 16 which forms a smoke pipe and will lead to a flue or chimney. It will be seen that said pipe 16 communicates with the inside of chamber 12^a. The member 12 has a plurality of spaced cylindrical openings 12^b extending there-through adjacent its bottom, which form passages connecting the space between members 12 and 13 with the space or chamber between member 12 and the outer shell 14. Said shell 14 adjacent its bottom and at its rear side has a projecting flange 14^a to which is connected a pipe 17 forming a return pipe for the air from the space or rooms which are heated. A cylindrical member 18 surrounds member 12^c and extends substantially to the top of plate 15, said member having a top plate 18^a and having a plurality of outwardly extending cylindrical flanges or hubs 18^b to which are connected the pipes or conduits 19 which will conduct the hot air to the rooms 100 to be heated. 105 110

In operation fuel will be supplied through the door 8 and through passage 7^a to the fire pot 7 being supported on grate 6 as shown in Fig. 1. The fuel will be burned in the fire pot 7 and the products of combustion will pass upwardly as shown by the arrows, the said products circulating in member 13 as indicated by said arrows and passing upwardly in member 12 around the passages 12^a and 10 around the member 12^c and thence out of the pipe 16. The hot air returning from the space to be heated will pass into the shell 14 through the pipe 17, thus filling the space surrounding fire pot 7 and partition 5^a. The 15 air will be somewhat heated by engagement with the walls of the fire pot and will pass up about member 12 and through the openings or passages 12^b between members 12 and 13 and thence upwardly through member 12^c 20 into member 18 and out through the pipes 19 by which it will be carried to the rooms to be heated. It will be seen that the air will be highly heated as it passes to the top of the furnace and out at the pipes 19. Draft can 25 be supplied to the fire in the usual way, by regulation of the door 10 and a damper (not shown) will be supplied in the pipe 16. It will be seen that the air passing into the furnace through pipe 17 will engage a large 30 area of heated surface as it passes upwardly and through the member 12^c, so that it is very effectively heated and practically all of the heat supplied by the fuel is absorbed.

Referring to Figs. 3 and 4, a furnace structure is shown, comprising the base plate 25 adjacent one side of which rises the wall or partition 25^a connecting with the horizontal partition 25^b, said partitions having a circular flange 25^c adapted to support the grate 26. While this grate may be of any usual and desired form, in the embodiment of the invention illustrated it is shown as a plate having transverse slots therein. A member 27 is supported upon the partition 25^a, the same having a substantially cylindrical portion forming the fire pot 27^a, the same having the parallel walls 27^b extending at its forward side to form between them a charging passage 25^b. This passage will be closed at its front by a charging door 28 of any suitable construction, and the front of the ash pit below the grate 26 will be closed by the ash door 28^a having the draft openings 28^b therein adapted to be controlled by the plate 28^c 45 carried on the screw 28^d having a handle at its outer end and threaded into the door 28^a. The member 27 may have a double wall forming a chamber 27^c thereabout and the same has the top 27^d projecting rearwardly as a flange. The flange 27^d and top 27^a are provided with lugs for positioning a cylindrical casing 30^a extending upwardly therefrom and supporting the top 29 of the furnace. A cylindrical casing 30 extends from base 50 plate 25 to the top 29, the same extending

upwardly alongside of the members 27^b and across the top thereof as shown in Fig. 3, said member 29 having depending flanges surrounding the casings 30^a and 30. The casing 31 is supported on the top 27^d having a central cylindrical portion 31^a with an open bottom disposed centrally thereof and over the fire pot 27^a, thus forming an annular chamber 31^b. The member 31 has the central opening at its top through which extends a conduit 32 extending through the top 29 and having a flange above said top on which is received a cover plate 33 having a handle 33^a thereon. The member 31 has a boss at one side of its top in which is threaded the stem or hot water outlet pipe 34 which extends through the top 29, and said member has a boss at its lower portion receiving the pipe 35 extending outwardly through casings 30^a and 30 which is connected to the pipe 35^a extending inwardly 65 through casing 30 and secured in a boss on the rear wall of member 27, pipes 35 and 35^a thus forming a passage between chambers 31^b and 27^c. A pipe 36 is threaded into a boss in the lower portion of member 27 which 70 communicates with chamber 27^c and extends outwardly through chamber 30, said pipe forming a return pipe for the water returning from the rooms to be heated. Said pipe also has connected thereto another pipe 37 controlled by a valve 38 which may constitute a feed water pipe. The top 29 has an upwardly extending boss 29^a about which extends the smoke pipe 39.

In operation water will be supplied to 100 chambers 27^c and 31^b through the pipe 37. Fuel will be charged into the fire pot through passage 27^b and the door 28 as indicated at 40. The products of combustion from the fuel will pass upwardly into the portion 31^a of 105 member 31 outwardly around the bottom of member 31 and upwardly at the sides thereof between the same and casing 30^a, the same passing out at the smoke pipe 39. The heat will be conserved by the insulating chamber 110 of air between casings 30^a and 30. The hot water or steam, as the case may be, will pass from the upper portion of member 31 out through the pipe 34 to the radiators and will return through the pipe 36 to the lower portion of chamber 27^c. This water will be heated by the heat of the fire pot 27 and will pass through the pipes 35^a and 35 to the bottom of chamber 31^b where it will be further heated by the said products of combustion. 115 The draft can be regulated as usual by the member 30. It will be seen that owing to the shape of member 31 that the heated products of combustion will bear upon all sides thereof and that a comparatively narrow body of water is formed in chamber 31^b which can be effectively heated. If desired, after the furnace is in operation, fuel can be charged through the member 32 by removing the cover 33 and fuel can thus be built up to the top of 120 125 130

the fire pot 27 and extending somewhat thereabove.

From the above description it is seen that applicant has provided a simple and very efficient construction of stove or furnace and one which will have a high degree of efficiency in the use of the fuel. The device is such that it can be built in various sized units, and can be easily and inexpensively constructed. The 10 device has been amply demonstrated in actual practice and found to be very successful and efficient.

It will, or course, be understood that various changes may be made in the form, details, 15 arrangement and proportions of the parts, without departing from the scope of applicant's invention, which, generally stated, consists in a device capable of carrying out the objects above set forth, in the novel parts and 20 combinations of parts disclosed and defined in the appended claims.

What is claimed is:—

1. A furnace having in combination, a fire pot, a substantially cylindrical chamber open 25 at its bottom and closed at its top, spaced directly above said fire pot and of substantially the same diameter as said fire pot, an annular chamber having a closed bottom disposed in a horizontal plane substantially at the bottom 30 of said cylindrical chamber, said annular chamber surrounding said cylindrical chamber and extending over the top thereof and adapted to receive the medium heated and distributed by the furnace, a second annular 35 chamber surrounding said first mentioned annular chamber and communicating at its bottom with said cylindrical chamber to receive the products of combustion, a conduit leading from said second annular chamber to a chim-

ney and a third annular chamber surrounding 40 said second annular chamber, the outer wall of which forms the outer wall of said furnace, said third annular chamber extending to the bottom of said furnace, passages leading from said third annular chamber into 45 said first mentioned annular chamber at each side thereof, a substantially horizontal plate extending about said fire pot and forming the bottom of said second annular chamber and a door equipped passage for charging fuel into 50 said fire pot disposed below said plate.

2. A furnace having in combination, a fire pot, a substantially horizontal plate extending about the top of said fire pot, a door equipped passage leading to said fire pot for 55 charging fuel thereinto below said plate, a substantially cylindrical member spaced slightly above said fire pot and plate having a closed top and an open bottom, the lower edge of said member being disposed in horizontal 60 plane, the diameter of said member being substantially the same as the diameter of said fire pot, an annular chamber surrounding said member, said chamber being closed at its bottom and adapted to receive the medium 65 heated and distributed by the furnace, a casing surrounding said annular chamber and spaced from the wall thereof and having a top wall extending over said annular chamber and spaced from the top thereof, said last 70 mentioned casing forming a passage for the products of combustion about said annular chamber and over the top thereof and a conduit extending into said first mentioned annular chamber through which said medium is 75 adapted to pass.

In testimony whereof I affix my signature.
AUGUST ERICKSON.
